CLAIM

The ornamental design for a beverage filter, as shown and described.

DESCRIPTION

FIG. 1 is a top, front, and right side perspective view of a beverage filter, showing my new design;

FIG. 2 is a top plan view thereof;

FIG. 3 is a right side elevational view, the left side being a mirror image thereof; and,

FIG. 4 is a bottom plan view thereof.

FIG.1.

FIG.2.

FIG. 3.

FIG. 4.
